UNITED STATES PATENT OFFICE.

ALFRED W. WADEWITZ, OF SCHLEISINGERVILLE, WISCONSIN.

LEAF-HOLDER.

1,399,675.

Specification of Letters Patent.

Patented Dec. 6, 1921.

Application filed November 22, 1920. Serial No. 425,734.

To all whom it may concern:

Be it known that I, ALFRED W. WADEWITZ, a citizen of the United States, and resident of Schleisingerville, county of Washington, 5 and State of Wisconsin, have invented certain new and useful Improvements in Leaf-Holders; and I do hereby declare that the following is a full, clear, and exact description thereof.

10 My invention relates to book supports and its purposes are to provide a support of this character which is adjustable in various respects in order to accommodate books of different sizes; to provide a book support 15 which is foldable into compact form so as to take up but a minimum of space when not in use; to provide novel leaf-retaining fingers operable from a single conveniently located point to released position to permit 20 turning of the leaves, and to provide all of the foregoing in a structure embodying many features of beneficial novelty whereby a book may be supported for convenient use and whereby the support itself may be quickly 25 and easily adjusted and folded.

My inventive idea is capable of embodiment in various mechanical structures, one of which is illustrated in the accompanying drawings, but it is to be understood that the 30 structure shown is merely intended to disclose the essential features of my invention in a preferred form, and that its scope is as defined in the appended claims.

In the drawings, wherein like characters 35 of reference designate corresponding parts in the different views:

Figure 1 is a front elevation, with parts shown in section, of a book support embodying the essential features of my invention,

40 Fig. 2 is a side elevation of the book support, as shown in Fig. 1.

Fig. 3 is a front elevation of the book support folded; and

Fig. 4 is a detail plan view of one of the 45 leaf retaining devices showing its position in dotted lines when moved to released position.

Referring to the drawings in detail, 10 designates a tubular standard carrying at 50 its upper end a block 11 and at its lower end having hinged thereto the shorter arms of a pair of L-shaped members 12 which are of duplicate construction and carry the leaf retaining fingers to be hereinafter more particularly specified. The members 12 are of tubular form and are hinged to the stand-

ard 10 at opposite points, so that when they are swung upon their pivots to folded position as shown in Fig. 3 they are disposed in parallelism with respect to the standard 60 and to opposite sides thereof, in which position they are retained by catches 13 carried adjacent their outer ends engaging spring-pressed keepers 14 in the block 11. One of these members 12 carries an extension piece 65 15 in which is mounted a catch 16, and said extension piece is adapted to underlie an adjacent portion of the other member 12 when these members are swung to extended or operative position, in which position the 70 catch 16 engages a spring pressed keeper 17 in the second member 12 to lock said members together and prevent any movement of them until the catch is released.

Slidable on each longer arm of the members 12 is a block 18 which may be locked in any adjusted position along said arm by a set screw 19. These blocks each have pivoted thereto a tubular member 20 which may be swung to lie when in folded position in parallelism to the longer arm of its associated member 12, or may be swung to extended position at right to its associated arm of the members 12. In either position it is locked by a spring pressed catch 21 engaging with one or another of a pair of keeper members 22 carried by the block. Slidable in each tubular member 20 is the shank of an extensible foot member 23 which carries a small shelf 24 upon which an edge of the 90 book supported by the device rests. These foot members are retained in desired adjusted positions by means of set screws 24' in the tubular members 20 engaging the shanks aforementioned.

A longitudinal slot is cut in the outer end of the longer arm of each member 12 and to either side of such slots extends laterally outwardly from the arms a plate 25. Extending through the slot of each member 12 is an arm 26 carried at the outer end of a rod 27, one of which extends partially through each member 12 and is normally pressed in an outward direction by a spring 28. The arms 26 project between the pairs of plates 25, respectively, and at their outer ends, each have pivoted thereto a member 29 provided with a cam slot 30 within which operates a roller 31 carried by the plates 25. Adjustable with respect to each member 29 by reason of a spring pressed latch 33 is a support 32 for a threaded stem 34, mov-

able toward and away from the longer arm of its associated member 12 to retain the leaves of a book arranged between it and said arm. For the purpose of obtaining a quick adjustment of the threaded stem 34 a spring pressed dog 32' is pivoted to the outer end of the arm 32 and is threaded to engage the stem 34. When the dog is released, the stem can be readily slid up and down to the approximate position desired, after which the final adjustment for clamping the leaves to the arm 12 is obtained by screwing down upon the stem 34.

Arranged in spaced parallelism with respect to the standard 10 and fixed relatively thereto is a rod 35 and slideable thereon is a block 36 retained adjacent either end of said rod by means of a catch 37. This block has fixed thereto one end of a rod 38 which extends downwardly through the standard and has flexible connections 39 with respective rods 27. As is apparent, by moving the block 36 upwardly upon the rod 35 the rods 27 are drawn inwardly which results in the rollers 31 acting upon the cam slots 30 to throw the leaf retaining stems 34 outwardly to release the leaves of a book carried by the support and permit said leaves being turned, the springs 28 acting to return the parts mentioned to normal leaf-engaging position upon release of the block 36, as is apparent.

The entire structure as described in the foregoing may be supported in a rearwardly inclined position upon a flat surface by means of a leg 40 pivoted to the standard and foldable into close relationship therewith.

From the foregoing, it will be observed, that I have provided a book support which is adjustable in various respects, which may be compactly folded, which is of simple construction, easy to operate and which is efficient in use.

Having thus fully described my invention, what I claim as new, and desire to secure by Letters Patent, is:—

1. A book support of the character described comprising a standard, arms pivoted to said standard, leaf retaining means carried by the arms, and movable means carried by the standard, the latter controlling the movement of the leaf retaining means.

2. A book support comprising a standard, arms pivoted to and foldable with respect to said standard, blocks slideable on said arms, tubular members pivoted to and foldable with respect to said block and arms, ex-

tensible foot members carried by said tubular members, and leaf retaining devices carried by said arms.

3. A book support of the character described comprising a standard having arms pivoted thereto, a supporting element carried by the arms and standard, leaf retaining means pivotally connected to the ends of said arms, a block slideable on the standard, the latter controlling the movement of the leaf retaining means.

4. In a book support, the combination of a standard and tubular arms pivoted thereto and adapted to fold with respect to said standard, spaced plates at the outer end of each arm, an arm movable between said plates and controlled by a movable rod within said arm, and a leaf retaining element pivoted to said arm and adapted to be thrown into and out of operative position by the movement of said rod.

5. In a book support, the combination of a standard and tubular arms pivoted thereto and adapted to fold with respect to said standard, spaced plates at the outer end of each arm, an arm movable between said plates and made integral with a rod movable within said arm, means on the standard for controlling the movement of said rod, and a leaf retaining element pivoted to said arm and adapted to be thrown into and out of operative position by the movement of said rod.

6. A book support of the character described comprising a standard, arms pivoted thereto and having leaf retaining means positioned at their outer ends, means slideable with respect to said arms for operating said retaining means, and means slideable on said standard for controlling the movement of the first said means.

7. A book support of the character described comprising a standard and arms carried thereby, spring controlled rods slideable within said arms, an adjustable leaf retaining element pivoted to each of said rods, means carried by the standard for controlling the movement of said rod, and a stationary element carried by said arm and adapted to coact with the leaf retaining element to cause the movement of the latter upon the movement of the rod within said arm.

In testimony that I claim the foregoing I have hereunto set my hand at Schleisingerville, in the county of Washington and State of Wisconsin.

ALFRED W. WADEWITZ.
